UNITED STATES PATENT OFFICE.

HENRY M. WILLIAMS, OF FORT WAYNE, INDIANA, ASSIGNOR OF ONE-FOURTH
TO FRANZ BURGER, OF SAME PLACE.

DESIGN FOR A SPOON OR SIMILAR ARTICLE.

SPECIFICATION forming part of Design No. 29,725, dated November 29, 1898.

Application filed August 8, 1898. Serial No. 688,122. Term of patent 14 years.

To all whom it may concern:

Be it known that I, HENRY M. WILLIAMS, a citizen of the United States, residing at Fort Wayne, in the county of Allen and State of Indiana, have invented and produced a new and original Design for Bowls of Spoons or Similar Articles, of which the following is a specification, reference being had to the accompanying drawings, forming part thereof.

In the drawings, Figure 1 is an obverse plan of the bowl embodying my design. Fig. 2 is a reverse plan, and Fig. 3 is a side view showing a handle.

The leading feature of my design consists in the shape or configuration of the bowl or body A, comprising, essentially, three curved and rounded extensions merging into each other. Thus in the drawings the bowl A on its obverse side presents an outline embrac-

ing three curves jointed at their ends, so that 20 the bowl presents an appearance of three rounded extensions a, with indentations b between them, and these extensions have on their reverse sides rounded or curved outlines merging into each other, as at c, and the whole 25 embodies a design for a bowl for spoons or similar articles.

What I claim is—

The design for a spoon or similar article, substantially as shown and described. 30

In testimony whereof I have signed my name to this specification in the presence of two subscribing witnesses.

HENRY M. WILLIAMS.
